UNITED STATES PATENT OFFICE

HARRY E. GOSCH, OF NORTH TONAWANDA, NEW YORK, ASSIGNOR TO CREO-DIPT COMPANY, INC., OF NORTH TONAWANDA, NEW YORK, A CORPORATION OF NEW YORK

MACHINE FOR STAINING SHINGLES

Application filed February 18, 1927. Serial No. 169,206.

This invention relates to a machine which has been more particularly designed for staining bundles of shingles.

One of its objects is the provision of a machine of this character which is simple, compact and rugged in construction, which is reliable and efficient in operation, and which is not liable to get out of order.

Another object of the invention is to provide a power-driven machine of this character having means for lowering and raising the bundles of shingles into and out of the stain-tank and for automatically arresting the movement of the bundles when they reach the end of their predetermined travel in either direction.

In the accompanying drawings:—

Figure 1 is a front view of the machine embodying my invention. Figure 2 is a side view thereof. Figs. 3 and 4 are fragmentary rear views thereof showing the position of the parts during the lowering and raising movements of the shingle-carrier or basket, respectively. Figure 5 is a fragmentary rear view of the belt-shifter bar and its operating lever, the parts being shown in their normal or neutral position. Figure 6 is a fragmentary sectional side view of the trip device for automatically controlling the downward movement of the shingle-carrier. Figure 7 is a side view of a modified form of the invention. Figure 8 is a rear view thereof.

Similar characters of reference indicate corresponding parts throughout the several views.

In its general organization, this improved machine comprises a tank containing a quantity of stain into which the bundles of shingles are dipped, a carrier or basket for the shingle-bundles suspended for movement relative to the tank, means for lowering and raising the carrier into and out of the tank, and means for automatically arresting the movement of said carrier when it reaches the end of its predetermined travel in either direction.

Referring now to the embodiment of the invention illustrated in Figs. 1-5, inclusive, 10 indicates the tank for the stain which rests on the floor and which may be rectangular

or any other desired shape. This tank is open at its top and in its bottom is a suitable agitator 11 mounted on a shaft 12 for keeping the stain thoroughly mixed. Said agitator-shaft may be driven by a belt 13 and pulley 14 from any source of power.

Rising from the opposite side walls of the tank are columns or channel beams 15 on which the shingle-carrier or basket 16 is guided for vertical movement into and out of the tank. This carrier preferably consists of sheet metal side walls 17, and a forwardly inclined bottom made up of a series of rollers 18 journaled at their ends in said side walls. Below its upper end the carrier has a plurality of transverse bars 19 between which and the rollers 18 the bundles of shingles are placed, the bars serving to hold the latter down into the stain when the carrier is submerged therein. At its rear or discharge end 20 the carrier has a downwardly swinging door 20 which is normally held in its closed position by spring clamps 21 or other equivalent means. During the dipping operation, this door is closed to prevent the shingle-bundles 25 from falling out of the carrier, while in its open position, shown in Fig. 2, the same serves as a platform for supporting the bundles during their discharge from the dipping machine. The carrier may be open at its front or feed end and the bundles of shingles are placed side by side in an upright position, as shown by dotted lines in Fig. 1.

The carrier is guided for vertical movement on the columns 15 and for this purpose 30 has guide rollers 22 engaging the channels of said columns, these rollers being mounted on the ends of a shaft 23 secured to the carrier. Near its upper end, the carrier has a suspension bar or member 24 which passes 35 through longitudinal slots 25 in the columns and whose outer ends are connected to an elevating mechanism which will presently be described. The engagement of the suspension bar with the column-slots prevents lateral swaying of the carrier during its raising and lowering movements.

The elevating mechanism for the carrier 40 preferably consists of a pair of endless chains 26 which pass at their lower ends 45

around corresponding sprocket wheels 27 loosely mounted on the agitator shaft 12 while their upper ends pass around sprocket wheels 28 fixed on the ends of a driven shaft 29 journaled in bearings 30 attached to the columns 15. Each chain is connected by a bolt or other fastener 31 to the corresponding ends of the suspension bar 24, so that as the chains are driven in one direction or the other, the shingle-carrier is accordingly moved to bring it into or out of the stain-tank 10. Counterweights 32 applied to each chain serve to hold the carrier in its elevated position. Mounted on the driven shaft 29 are loose pulleys 33, 34 and a tight pulley 35, the pulley 33 being connected by a straight belt 36 with the corresponding pulley fixed on a driving shaft 37 and the companion pulley 34 being connected by a crossed belt 38 with a similar pulley on said driving shaft. Thus, when the belt 36 is shifted on to the tight pulley 35, the shaft 29 is driven in a clockwise direction to lower the carrier into the tank, and when the belt 38 is shifted on to the tight pulley, said shaft is driven in a counter-clockwise direction to elevate the carrier. These belts are shifted into and out of operative engagement with the tight pulley 35 by a laterally-shiftable bar 39 guided near its ends in brackets 40 secured to the columns 15 and carrying coupling yokes 41 embracing the corresponding belts 36, 38. This belt-actuating bar is shifted in one direction or the other by an operating lever 42 fulcrumed at 43 to an arm 44 attached to the adjacent column 15. Normally, this operating lever is held in a substantially vertical neutral position, shown by full lines in Figs. 1 and 5 and by dotted lines in Figs. 3 and 4, by a vertically-swinging locking pawl 45 engaging a notch 46 in the belt-shifter bar and held therein by a spring 47. A trip arm 48 connected by a link 49 with a supplementary actuating lever 50 located adjacent the handle of the operating lever 42 serves to effect the release of the locking pawl from the bar 39 to permit shifting the latter in either direction when desired. A coil spring 51 attached at one end to one of the columns 15 and at its other end to the belt-shifter bar acts to constantly urge the latter to its neutral position.

Means are provided for automatically arresting the movement of the shingle-carrier 16 when it reaches the end of its predetermined travel in either direction, this mechanism operating in conjunction with the belt-shifting bar 39 and its associated parts. To this end, the mechanism for arresting the downward movement of the carrier consists of a vertically-movable plunger or locking bolt 52 located at one side of the machine and guided in brackets 53, its upper end having a tooth 54 arranged to interlock with either of two notches 55, 56 located in the lower

edge of the bar 39 and its lower end having a coil spring 57 applied thereto and interposed between the adjacent guide bracket and a collar 58 fixed to the plunger for constantly urging the same upwardly into engagement with said bar. The lower end of the plunger is bent laterally to form a tappet arm 59 with which a trip lug 60 fixed on the side wall of the carrier is adapted to engage as the latter approaches the end of its lowering movement, as shown in Fig. 6. When the operating lever 42 is shifted from the dotted line to the full line position shown in Fig. 3, the belt 36 is shifted on to the drive pulley 35 to turn the chains 26 in the proper direction to lower the basket. In shifting the bar 39 to the position shown, it is held in such position by the plunger-tooth 54 interlocking with the notch 55 thereof. As the carrier reaches its immersed position in the tank, its trip lug 60 engages the tappet arm 59 of the plunger pulls the latter downwardly with it, thereby releasing the locking tooth from the belt-shifter bar and permitting the spring 51 to return it and the operating lever to neutral position. For the purpose of positively holding the carrier down in the tank, while the shingles are being covered with the stain, catches 61 may be applied to the suspension bar 24 for engagement with the flanged upper edge of the tank 10 or other fixed part of the machine, as seen by dotted lines in Fig. 3.

In lifting the carrier from the tank, the operating lever is shifted to the position shown by full lines in Fig. 4, in which position the crossed belt 38 is engaged with the tight pulley 35. The automatic means for arresting the upward movement of the carrier and shifting the controlling elements to their neutral position consists of an arm 62 rising from the carrier 16 and terminating in its upper end in a cam face 63 which is adapted to contact with a roller 64 on the belt-shifter bar 39 as the carrier approaches its elevated position. Said bar and its operating lever 42 are held in the position shown by full lines in Fig. 4 by the plunger-tooth 54 engaging the notch 56 in the bar. When the cam 63 engages the roller 64, it automatically shifts the bar 39 and operating lever to the dotted line position shown in Fig. 4, it being understood that the parts are normally retained in such position by the pawl 45 interlocking with the notch 46 in said bar.

Briefly stated, the operation of the machine is as follows:—

Assume the parts to be in the position shown in Figs. 1 and 2, with the swinging door in its raised or closed position. After loading the carrier 16 with the bundles of shingles, the same is lowered into the stain-tank 10 by shifting the operating lever 42 from the dotted line position to the full line position shown in Fig. 3. When it is fully immersed in the tank, the carrier is automati-

cally stopped and the operating lever is re- turned to its neutral position in the manner heretofore described. The carrier is allowed to remain in the tank for about two minutes, during which time the shingles are thorough- 70
ly coated with the stain. The inclined dis- position of the shingle-bundles in the carrier not only permits the ready displacement of air between the shingles of a bundle but it also results in a rapid and uniform distribution of the stain over the shingles. After the shingles have been immersed for the required period of time, the carrier is lifted from the tank by first releasing the catches 61 and then shifting the operating lever to the full line position shown in Fig. 4. Upon reaching its elevated position shown in Figs. 1 and 2, the carrier is automatically arrested in the manner previously described, the door 20 is dropped and the bundles of stained shingles are discharged from the carrier, after which the latter is ready to receive another supply of shingles. The inclined roller bottom of the carrier materially facilitates the discharging of the shingle-bundles, it being only necessary to give them a slight push to effect their re-
moval.

In the modified form of the invention shown in Figs. 7 and 8, the carrier 65 is raised and lowered through the medium of suspension elements in the form of fixed nuts 66 applied to its side walls and engaging upright screws 67 driven from a driving shaft 68 by intermeshing bevel gears 69. This shaft is driven in one direction or the other by belts and pulleys in the manner set forth in the first described construction. The belt-shifting bar is indicated at 70 and its operating lever at 71, the latter having a locking latch 72 controlled by a supplement- 95
ary hand lever 73 for holding it in neutral position. This embodiment of the invention also has a plunger or locking bolt 74 ar- ranged to interlock with the belt-shifter bar when the parts are in the position shown by dotted lines in Fig. 8, and is adapted to be automatically released therefrom when the carrier reaches the end of its downward movement by a trip arm 75 arranged in the path of a collar 76 on said plunger.

For the purpose of heating the stain in the tank and permit its more ready penetra- 100
tion into the shingles, a steam pipe 77 or similar heating element may be applied to one of the inside walls of the tank, as shown in Fig. 1.

I claim as my invention:—

1. A machine of the character described, comprising a tank containing a fluid for staining shingles, a carrier for the shingles guided for movement into and out of said tank, an elevating mechanism, means for driving the elevating mechanism in one direction or the other, means for connecting the carrier with said mechanism, means for

controlling the engagement of the elevating mechanism with the driving means, a locking device for holding said controlling means in its operative engaged position, and means on the carrier for releasing said locking device 70
from the controlling means at a predetermined point in the travel of said carrier.

2. A machine of the character described, comprising a tank containing a fluid for staining shingles, a carrier for the shingles guided for movement into and out of said tank, an elevating mechanism, means for driving the elevating mechanism in one direction or the other, means for connecting the carrier with said mechanism, means for controlling the engagement of the elevating mechanism with the driving means, a yield- 75
able element for constantly urging said controlling means to seek a neutral inoperative position, a locking device for holding said controlling means in its operative engaged position, and means on the carrier for re-
leasing said locking device from the controlling means at a predetermined point in the travel of said carrier.

3. A machine of the character described, comprising a tank containing a fluid for staining shingles, a carrier for the shingles guided for movement into and out of said tank, a driving shaft having tight and loose 90
pulleys thereon, belts normally engaged with said loose pulleys and shiftable on to said tight pulley for rotating said shaft in one direction or the other, elevating devices oper- 95
atively connected with the driving shaft and the carrier, a belt-shifter bar including means for holding it in a neutral inoperative position, a locking device for holding said bar in an operative engaged position, and means on the carrier for releasing said locking de- 100
vice from the belt-shifter bar at a predeter-
mined point in the travel of said carrier.

4. A machine of the character described, comprising a tank containing a fluid for staining shingles, a carrier for the shingles guided for movement into and out of said tank, a driving shaft having tight and loose 110
pulleys thereon, belts normally engaged with said loose pulleys and shiftable on to said tight pulley for rotating said shaft in one direction or the other, elevating devices oper- 115
atively connected with the driving shaft and the carrier, a belt-shifter bar, an operating lever therefor, a spring for urging said bar to a neutral inoperative position, a locking bolt for holding said bar in an operative position, and a trip element on the carrier adapted to release said bolt from the belt-shifter bar at a predetermined point in the travel of said carrier.

5. A machine of the character described, comprising a tank, containing a fluid for staining shingles, a carrier for the shingles guided for movement into and out of said 130
carrier.

- 5 tank, a driving shaft having tight and loose pulleys thereon, belts normally engaged with said loose pulleys and shiftable on to said tight pulley for rotating said shaft in one direction or the other, elevating devices operatively connected with the driving shaft and the carrier, a belt-shifter bar, an operating lever therefor, a spring for urging said bar to a neutral inoperative position, a locking bolt for holding said bar in either of two operative positions for raising or lowering the carrier, and trip elements on said carrier for automatically effecting the release of the locking bolt from the belt-shifter bar when the carrier approaches the end of its raising and lowering movements.
- 10 6. A machine of the character described, comprising a tank containing a fluid for staining shingles, a carrier for the shingles guided for movement into and out of said tank, a driving shaft having tight and loose pulleys thereon, belts normally engaged with said loose pulleys and shiftable on to said tight pulley for rotating said shaft in one direction or the other, elevating devices operatively connected with the driving shaft and the carrier, a belt-shifter bar, an operating lever therefor, a spring for urging said bar to a neutral inoperative position, a yieldable locking bolt for holding said bar in an operative position, and means on said carrier for moving the belt-shifter bar to neutral position when the carrier approaches the end of its raised position.
- 15 7. A machine of the character described, comprising a tank containing a fluid for staining shingles, a carrier for the shingles guided for movement into and out of said tank, a driving shaft having tight and loose pulleys thereon, belts normally engaged with said loose pulleys and shiftable on to said tight pulley for rotating said shaft in one direction or the other, elevating devices operatively connected with the driving shaft and the carrier, a belt-shifter bar, an operating lever therefor, a spring for urging said bar to a neutral inoperative position, a yieldable locking bolt for holding said bar in an operative position, a roller on the belt-shifter bar and an arm rising from the carrier and having a cam face adapted to engage said roller to shift said bar to its neutral position when said carrier approaches its raised position.
- 20 8. A machine of the character described, comprising a tank containing a fluid for staining shingles, an elevator frame rising from said tank, a suspension member guided on said frame for movement lengthwise thereof, a carrier for the shingles attached to said suspension member, elevator chains arranged on opposite sides of said frame and connected to the corresponding ends of said suspension member, and driving means for said chains.
- 25 9. A machine of the character described, comprising a tank containing a fluid for staining shingles, an elevator frame rising from said tank, a suspension member guided on said frame for movement lengthwise thereof, a carrier for the shingles attached to said suspension member, elevator chains arranged on opposite sides of said frame and connected to the corresponding ends of said suspension member, driving means for said chains, an operating device for controlling said driving means to govern the movement of said chains in a direction to arise or lower the carrier, means for constantly urging said operating device to its neutral position, and means for holding said device in different operative positions, said carrier automatically controlling the release of said holding means at a predetermined point in its travel.
- 30 10. A machine of the character described, comprising a tank containing a fluid for staining shingles, an elevator frame rising from said tank, a suspension member guided on said frame for movement lengthwise thereof, a carrier for the shingles attached to said suspension member, elevator chains arranged on opposite sides of said frame and connected to the corresponding ends of said suspension member, driving means for said chains, an operating device for controlling said driving means to govern the movement of said chains in a direction to raise or lower the carrier, means for constantly urging said operating device to its neutral position, a yieldable locking bolt for holding said device in different operative positions, a trip on said carrier for releasing said bolt from the operating device when the carrier reaches the end of its movement in one direction, and a member on said carrier arranged to disengage the operating device from said bolt when the carrier reaches the end of its movement in the opposite direction.
- 35 11. A machine of the character described, comprising a fluid for staining shingles, an elevator frame rising from said tank, a suspension member guided on said frame for movement lengthwise thereof, a carrier for the shingles attached to said suspension member, an elevating mechanism operatively connected to said suspension member for moving the carrier into and out of the tank, and catches on said suspension member for holding the carrier in its immersed position in the tank.
- 40 12. A machine of the character described, comprising a tank containing a fluid for staining shingles, an elevator frame rising from said tank, a suspension member guided on said frame for movement lengthwise thereof, a carrier for the shingles attached to said suspension member, endless elevator chains arranged on opposite sides of said

frame and having one of their longitudinal stretches connected to the corresponding ends of said suspension member, driving means for said chains, and weights applied to said chains for normally holding the carrier in its raised position.
